[57] CLAIM

The ornamental design for vehicle top support for three-way sign display, as shown and described.

DESCRIPTION

FIG. 1 is a perspective view of a vehicle top support for three way sign display, showing my new design;

FIG. 2 is a fragmentary top perspective view, shown on an enlarged scale, of the interior side of the support; FIG. 3 is a similar view on a slightly smaller scale of the exterior side;

FIG. 4 is a top plan view thereof, shown on an enlarged scale;

FIG. 5 is a side elevational view thereof;

FIG. 6 is a cross-sectional view thereof, taken along line 6—6 of FIG. 5.

The broken line disclosure of FIG. 1 of a vehicle top, sign panels and two additional sign supports with mounting means is for illustrative purposes only and forms no part of the claimed design.
